C. L. CONE.

FOLDING DEVICE FOR SEWING MACHINES.

APPLICATION FILED MAR. 7, 1905.

1,115,400.

Patented Oct. 27, 1914.

UNITED STATES PATENT OFFICE.

CHARLES L. CONE, OF PORTSMOUTH, VIRGINIA, ASSIGNOR TO THE UNION SPECIAL MACHINE COMPANY, OF CHICAGO, ILLINOIS, A CORPORATION OF ILLINOIS.

FOLDING DEVICE FOR SEWING-MACHINES.

1,115,400.

Specification of Letters Patent.

Patented Oct. 27, 1914.

Application filed March 7, 1905. Serial No. 248,818.

To all whom it may concern:

Be it known that I, CHARLES L. CONE, a citizen of the United States, residing at Portsmouth, in the county of Norfolk, State of Virginia, have invented certain new and useful Improvements in Folding Devices for Sewing-Machines, of which the following is a description, reference being had to the accompanying drawing and to the letters and figures of reference marked thereon.

My invention relates to an improvement in folding devices for attachment to sewing machines and particularly to a device for use upon what is known as a collaret machine, for use in securing a band upon the neck of undershirts and the like.

The collaret is preferably formed of a strip of material and is usually first folded in the center lengthwise, the folded edge being overseamed or formed with an ornamental edge seam; then the collaret or band is fed to a sewing machine through a folding guide which turns a hem on each raw edge of the strip and folds it in the center again and it is secured by a line or lines of stitching which pass through the folded edges and a main body fabric which is guided between the layers of the collaret strip.

The object of the present invention is to provide a special form of folding device for guiding this so-called "tipped" collaret so as to prevent any friction or strain upon the folded edge thereof or ornamental stitches on said edge, if it is provided with such, while the band is passing through the folder.

The invention also includes features for exerting the proper tension upon the band in its passage through the folder and for keeping the folded or folded and tipped edge in the recess or space prepared for it in the folder.

My invention, therefore, consists in the matters hereinafter described and referred to in the appended claims.

The invention is illustrated in the accompanying drawings in which—

Figure 1 represents a perspective view of a folding device constructed in accordance with my invention. Fig. 2 is a perspective view from the opposite side of Fig. 1. Fig. 3 is a face view looking in the direction of the arrow, Fig. 4. Fig. 4 is a section on

line 4—4 of Fig. 2, and Figs. 5 and 6 are respectively sections on lines 5—5 and 6—6 of Fig. 2.

In these drawings, A represents the flat portion or base piece of the folder, which is secured to the bed plate of the sewing machine in any suitable way, and upon which the body portion of the fabric to which the collaret is to be secured rests. This base piece is formed as shown, with folding and guiding recesses a, a, adjacent the stitch-forming mechanism of the sewing machine, which recesses gradually taper down from the widened portions b of the folder proper, and these tapering portions a, a, turn the edges of the collaret around the body fabric.

Attached to, or formed with the folding portion proper B, is a hollow ribbed portion C, in which the folded edge or tipped portion of the collaret is guided in the passage of the same through the folder, thus preventing any friction upon the said edge, whether it is provided with ornamental or overseaming stitching or not. A spring finger c is attached to the rear face of the folder portion proper B, and projects into the recessed rib C to properly guide and hold the edge or tipped portion of the collaret in said recess. The object of the recessed rib or guide in the folder is to provide room to take that portion of a collaret strip which, when the strip is laid out flat is at right angles to the body thereof. When the strip is in the folder, it occupies a vertical position, and the overseaming stitch or tipped portion of the collaret occupies a horizontal position and this space is provided in the walls of the folder for it.

As shown in the drawings, there are attached to the end of the folder proper B, farthest away from the stitch-forming mechanism, two vertically arranged curved plates D, spaced apart so that room is left between them for the passage of the tipped portion of the collaret and one of them is provided with a rib e, which at one end opens into the recessed rib C. Bands of metal F, attached to the two plates D hold the same properly spaced apart, and serve as walls parallel with the plates D to guide the strip or band to be sewed and flat springs G and H are provided to keep the tipped portion of the collaret in its proper position in the space between the plates D. 110

The flat portion of the folder, it will be noticed, has its upper surface on a line which if extended, would enter the recessed rib for the collaret tip, as shown in Fig. 5.

5 This is desirable, as the support or platform for the body of the garment must be on a line with the collaret and that portion of the fabric which is tipped as the latter must come to the very top.

10 As shown at *f*, an open groove is formed through the face of the attachment for threading the strip into the folder.

Having thus described my invention, what I claim as new and desire to secure by Letters Patent, is:—

15 1. A folding device comprising a body portion having along its length a channel-forming rib, the latter projecting from the back of the said body-portion and in a direction opposite that of the folding portion of said device, said rib having a channel formed therein for receiving the rib or selvage of the work.

20 2. A folding device comprising a body-portion having hem-turning devices at its opposite edges and between said devices, a channel for guiding the body of the work, and said body-portion also having between said devices a longitudinally extending channel-forming rib for receiving the rib or selvage of the work.

25 3. A folding device having a portion provided with hem-turning devices at its opposite edges, and adjacent each of said devices with a passage for guiding the body-part of a piece of binding, and said portion being also provided remote from said turning-devices with means for guiding the rib or selvage of said piece of binding, said means 30 being arranged at the junction of said body-part-guiding passages, and a plate for supporting another piece of work, said plate extending between the said hem-turning devices, substantially parallel to the said rib-guiding means and with its supporting surface at the lower edge of said means, whereby the edge of one piece of the work may be led between the hemmed edges of the other piece of the work and close to said rib or selvage.

35 4. A folding device the body-portion of which has a channel-forming rib extending from end to end thereof for receiving and guiding the selvage of the work, and said body-portion also having means on opposite sides of said rib for folding one portion of the work upon another and also for hemming the edges of both portions of the work.

40 5. A folding device for sewing machines including guiding walls forming a guiding recess for the body of the binding strip or band, said guiding walls being shaped at their outer edges to provide folding recesses 45 for folding the edges of the strip or band,

the outer wall between its edges having a recess therein to receive and guide a tip or rib projecting from the outer face of said strip or band intermediate its edges.

6. A folding device for sewing machines 70 including guiding walls forming a guiding recess for the body of the binding strip or band, said guiding walls being shaped at their outer edges to provide folding recesses for folding the edges of the strip or band, the 75 outer wall between its edges having a recess therein to receive and guide a tip or rib projecting from the outer face of said strip or band intermediate its edges, and means for holding said tip or rib within the guiding 80 recess.

7. A folding device for sewing machines, comprising guiding means for guiding and folding a strip or band to be sewed and means extending from the receiving to the 85 delivering end of the folding device for receiving and guiding a tip or rib projecting from said strip or band, intermediate its edges, and a spring finger rigidly secured to the guiding means for the strip or band and 90 operating to hold said tip or rib within its receiving and guiding means; substantially as described.

8. A folding device for sewing machines, comprising guiding walls, one of which has 95 a recess or space extending from the receiving to the delivering end of the folding device for receiving a tip or rib projecting from the central portion of the folded band, and having a spring for holding said tip or 100 edge in the space provided for it; substantially as described.

9. A folding and guiding device for a tipped collaret, having vertical guiding walls with a recess in one of the said walls 105 to receive and guide the tip or edge projecting from the central portion of the folded band, a flat support for the body portion of the fabric, said vertical walls terminating in recesses for folding and guiding the edges 110 of the strip or band around the body portion of the fabric; substantially as described.

10. The herein described guiding and folding device for collarets, comprising vertically arranged plates spaced apart, a 115 complementary guiding wall, a rib on one of said vertical spaced plates, a folder proper having symmetrically curved walls, and a recessed rib into which the rib on the vertical plate opens, and folding and guiding recesses for turning the edges of the strip around the body portion of the fabric; substantially as described.

11. The herein described guiding and folding device for collarets, comprising vertically arranged plates spaced apart, a complementary guiding wall, a rib on one of said vertical spaced plates, a folder proper having symmetrically curved walls, and a recessed rib into which the rib on the vertical 125

plate opens, and folding and guiding recesses for turning the edges of the strip around the body portion of the fabric, and a series of springs for holding the collaret tip 5 in the space provided for it; substantially as described.

12. A folder for fabrics having a passage therethrough for receiving the body of the material to be folded, means on the face of 10 the folder for folding the edges of the material; said folder also having a central guiding-channel extending along the length of the back of the folder; and a yielding guard located in said passage and between 15 the edge-folding means and the guiding-channel for controlling the work.

13. A folder for fabrics having a passage therethrough for receiving the body of the material to be folded; and also having a centrally-located guiding-channel extending along the length of the back of the folder; loop-portions oppositely disposed for folding the edges of the material; and a yielding guard located between the said loop portions 25 and the guiding channel.

14. A folder for fabrics having a passage for receiving the body of the material to be

folded; and also having a centrally disposed, longitudinally extending guiding channel in the back of the folder; means for 30 folding the edges of the work arranged on the face of the folder; and a flexible guard extending from the face of the folder across said passage into coöperative relation with said guiding channel.

15. A folder for fabrics comprising a body portion concavo-convex in cross section and having a flattened inlet end for receiving the material to be folded, edge-folding means on the concave side of the folder, 40 and a centrally located channeled rib extending along the convex side of the folder at an angle to the flattened inlet end, and means, located adjacent the mouth of the channel of said rib and extending into the 45 edge-folding means, coöperating with said channel for retaining one edge of the fabric in the latter.

In testimony whereof I affix my signature, in presence of two witnesses.
